ADJUSTING MECHANISM

Joseph P. Ruth and George H. Woelbing, Denver,
Colo., assignors to The Ruth Company, Denver, Colo., a corporation of Colorado

Application January 15, 1934, Serial No. 706,684

4 Claims. (Cl. 74—282)

This invention relates to improvements in adjusting mechanisms and has reference to a mechanical movement or mechanism by means of which an adjustable member can be moved to any of a plurality of predetermined positions by mechanical means.

In our copending application, Serial No. 696,991, filed November 7, 1933, a synchronizing clutch has been shown, described and claimed which is adapted for use on locomotive vehicles of different types. In the application just identified, the means for operating the clutch has not been described, but merely indicated, and it is for the purpose of operating this particular clutch mechanism that the present invention has been designed, although it is adapted for a large variety of other uses.

This invention relates, more particularly, to a mechanism by which an adjustable member can be automatically moved, by means of compressed air, into either one of four predetermined positions.

This invention can be most clearly described and will be most readily understood when reference is had to the accompanying drawing in which it has been illustrated in its preferred embodiment, and in which:

Fig. 1 is a diagram showing the principle of operation of the invention;

Fig. 2 is a diagram similar to that shown in Fig. 1, but in which a species of gear wheel has been substituted for the lever;

Fig. 3 is another modification in which a differential gear mechanism has been shown as substituted for the single gear in Fig. 2;

Fig. 4 is a top plan view of the mechanism shown in Fig. 3;

Fig. 5 is a vertical section through the preferred embodiment of the invention;

Fig. 6 is a transverse section taken on line 6—6, Fig. 5; and

Fig. 7 is a fragmentary section to a somewhat larger scale, showing a latching mechanism.

In the drawing reference numerals 8 represent cylinders in which are mounted for reciprocity, pistons 9. Attached to each piston is a piston rod 10 that extends through one of the cylinder heads, and has pivotally attached to it a connecting rod 11. The outer ends of the connecting rods are joined by a lever 12 which is preferably of a length equal to the distance between the piston rods. Air or steam or other fluid can be introduced to either end of the pistons through the pipes 13 and 14. In the embodiment shown in Fig. 1, the cylinders are both of

equal length and the strokes of the pistons are the same. Secured to the lever 12 is a rod 15 that carries the adjustable member 16. The different positions of the pivot pin 17 and of the adjustable member have been designated by letters *a*, *b*, *c*, and *d*. If we assume that the piston in the upper cylinder is moved towards the right from the full line to the dotted line position, then the end of the connecting rod will move towards the position designated by *b'*, and if the member 15 and the pivot pin 17 move in a straight line, the lower end of the lever where it is connected with the connecting rod will move to the position *b''*. After the piston has moved, the pivot pin 17 will be at the point indicated, *b*, and the member 16 will be at the point indicated by *b*. If the lower piston is now moved towards the right from the full line towards the dotted line position, the end of the connecting rod where it is joined to the lever will be at 10 the position designated *c'*, while the pivotal point between the upper connecting rod and the lever will be at the point designated *c*. Due to the fact that the pivot pin 17 has been shown as located below the middle of the lever, the distance *a b* is smaller than the distance *b c*, but by moving the pivotal point up to the center these two distances will be alike and if the point of connection is moved to a point above the center, then *a b* will be larger than *b c*. With the parts shown in their extreme right hand position, let us now assume that the piston in the upper cylinder is moved towards the left from the dotted to the full line position. The lever 12 will then rotate until its upper point of pivotal connection 20 with the connecting rod is at the point designated as *d'* and at the same time the lower end will be at the point indicated as *d''*, while the point 25 17 will be located at *d*. When the lower piston is moved from the dotted to the full line position, the lever 12 will be moved into full line position, and the cycle has been completed. It is clear from the description given that by means of a mechanism like that illustrated in Fig. 1, a member 16 can be moved to any one of four predetermined positions. By having the pivot point 17 to either side of the center, the two neutral points *b* and *d* can be spaced apart but if the pivotal connection 17 is at the center of the lever, these two points will coincide.

In Fig. 2 the idea has been carried forward slightly and instead of the lever 12, a gear wheel 12a has been substituted. This gear is provided with toothed segments 18 and the piston rods 11a are provided with rack teeth 19 that cooperate 55

with the gear segments 18. The adjusting member 15 has been shown as pivotally connected to member 12a at point 17a. The several positions of the adjustable member 16 have been indicated by letters *a*, *b*, *c* and *d*, the same as in Fig. 1.

Let us now assume that the piston in the upper cylinder is moved towards the right until it reaches the dotted line position, then the gear 12a will be rocked into the position indicated by 10 dotted lines and designated by reference numeral 20. Owing to the rolling connection between the gear and the rack of the lower piston rod, the movement of the part 12a will be slightly different from that of lever 12 in Fig. 1, but will be substantially the same. After the upper piston has been moved, the member 16 will occupy the position indicated by letter *b*. The lower piston is now moved towards the right from full line to dotted line position, whereupon the gear assumes the 20 position indicated by reference numeral 21, and the member 16 the position indicated by letter *c*. If the upper piston is now moved towards the left, the gear will assume the position indicated by reference numeral 22 and member 16 the position indicated by letter *d* and when the lower piston is returned to full line position, the gear will assume the position indicated by full lines.

In Figs. 3 and 4, the idea has been carried out still farther and instead of the lever or single gear, a differential gear mechanism has been employed which comprises two compound gears 23 and 24 which are identical in shape and size. Each of these gears has a bevel gear 25 and a spur gear 26, and both are rotatable about the 35 axis of the shaft 27. Connected with the shaft 27 and extending radially therefrom, is a stub shaft 28 on which is pivoted a pinion 29. A stub shaft, as just stated, is carried by the shaft 27 and the latter has attached to its upper end a lever 30 to which the adjusting member 15 is pivotally connected. The racks 11a are operatively connected with the spur gears and therefore when the pistons are moved, they will produce a rotation of the gears corresponding to the extent 40 and direction of the movement. Whenever one of the gears 23 or 24 is rotated relative to the other, it will produce a rotation of the shaft 27 in a manner well understood.

Let us now assume that the piston in the upper 50 cylinder in Fig. 3 is moved towards the right until it assumes the dotted line position. This will cause the wheel 23 to turn through a certain angle, thereby rotating the pinion 29 about its axis and rolling it a short distance along the gear 24 and this motion produces a slight angular movement of the shaft 27, which, in this case, moves the crank arm 30 to the position indicated by *b* in Fig. 4 and moves the adjustable member 16 to the corresponding position. If the piston 55 in the lower cylinder is moved towards the right from full line to dotted line position, the lower gear wheel will be rotated and this will produce a further movement of the stub shaft 28 in the same direction, thereby moving the end of the crank arm to the position *c* in Fig. 4.

It will be seen from Fig. 3 that the lower cylinder has been indicated as longer than the upper because, for the purpose for which the device is intended, the distance *b c* is preferably 70 larger than the distance *a b* and the stub shaft can only be connected with the pinion at the center of the latter, it is necessary to increase the length of the stroke of one of the pistons in order to obtain this discrepancy in the movement. 75 By reversing the motion of the piston in the upper

cylinder and moving it from dotted to full line position, the end of the crank arm is moved from *c* to *d* and when the piston in the lower cylinder is returned to full line position, the parts assume the position shown by full lines in Fig. 4.

5

The invention as outlined above is embodied in a practical mechanism which has been illustrated in Figs. 5, 6 and 7. This mechanism consists of a housing formed of two parts 31 and 32, each of which is provided with a flange 33 that is perforated for the reception of securing bolts 34. The upper portion 31 of the housing has a central cylindrical opening 35, in which is located a roller bearing 36. This bearing is held in place by means of a removable plate 37 that in turn is secured to the housing by means of bolts 38. An oil seal is provided which prevents oil from leaking out around the shaft 27. The inner surface of the housing member 31 has a downwardly extending circular bearing 39 and the lower member of the housing is also provided with a similar bearing 39. The lower housing has a cylindrical connection 40 that terminates in a flange 41 which is perforated for the reception of bolts 42 by means of which it is attached to the clutch 25 housing 43. An oil seal 44 is interposed between the flange 41 and the clutch housing 43. The shaft 27 extends down into the interior of the clutch housing and is provided with a crank arm 30 to the end of which the adjusting lever 15 is pivotally connected. Rotatably mounted in the circular bearings 39 are gear wheels 23 and 24 which are each provided with a bevel gear 25 and a spur gear 26. Surrounding the shaft 27 is a 35 collar 45 which is nonrotatably secured to the shaft and carries two oppositely extending stub shafts 46. Rotatably mounted on each stub shaft is a pinion 29. The collar is preferably provided with interconnected arms 47 and these are provided at their juncture with an opening 48 for 40 the reception of the outer end of the stub shaft so as to relieve the latter from excessive strains. Secured to the two housings 31 and 32 are cylinder and piston assemblies like those shown in Fig. 6. Each of these assemblies consist of a 45 cylinder 49 which is provided with cylinder heads 50 and 51. Located within the cylinder is a piston 52 that is connected to one end of the piston rod 53. This piston rod extends through an opening in the cylinder head 51 and terminates 50 in a socket portion 54. The cylinder head 51 has a cylindrical extension 55 that is provided with an outwardly extending flange 56 perforated for the reception of the securing bolts 57 by means of which the assembly is fastened to the housing 55 31. The inner end of member 55 has a bearing 59 through which a tubular rack 58 extends. The rack projects through the housing and has its other end slidably mounted in a bearing 60 secured to the housing by means of bolts 61. The 60 rack is provided with teeth 62 that cooperate with the spur teeth 26. The inner wall of the housing has a projection 63 that engages the outer surface of the rack bar and serves as a support for the latter. The rack bar is connected with 65 the socket 54 by means of pins 64 that project through elongated openings 65 so that there will be a lost motion connection between the piston rod and the tubular rack. Located within the tubular rack is a bar 66 that has its outer end 70 threaded connected with the socket 54 as indicated at 67. The bar 66 is provided with notches 68. The rack is provided with openings in which are located plugs 69. The inner ends of these plugs contact with the surface of the rod 66 or 75

with the bottoms of the notches. The bearings through which the rack moves are provided with openings 70 in which are located balls 71 and springs 72. The outer ends of these springs are 5 in contact with plugs 73 and the springs are under compression so as to tend constantly to move the balls inwardly. When the parts are in the position shown in Fig. 6, the ball at the left side of the housing will project into the opening in the 10 rack bar substantially half its diameter, and therefore it will form a positive lock which holds the rack against accidental movement. If the piston 52 is moved towards the right, the first part of this movement will cause the bar 66 to slide in the rack and move the plug 69 downwardly until it pushes the ball out of the opening, whereupon the rack is free to move towards the right. When the bar 66 has moved to the right as far as it can, the notch 68 near the right end, will arrive at 15 the position shown in Fig. 7 and therefore when the opening in the rack comes into alignment with the ball 71 at the right side, this ball will drop into the opening in the rack and latch the same against movement until the latch is released by 20 a reverse movement of the piston. Each of the cylinders is provided with the same latching means and the cylinder assemblies are alike, except for the length of the stroke, which can be varied to obtain the differential movement required. 25

For the purpose of this explanation, the specific valve mechanism by means of which the flow of air is controlled does not need to be described in detail, as it is clearly possible to introduce and exhaust the air by means of ordinary valves, but in Fig. 3 valves 74 have been diagrammatically shown and these are intended to represent valves that will alternately open the intake and exhaust from opposite ends of the piston, thereby enabling the operator to move the pistons in any direction. 30

From the above description it will be apparent that the objects desired can be attained by specifically different mechanisms and the invention 35 is therefore considered broader than the practical embodiment shown and applicant's desire to claim the invention as broadly as possible in view of the prior art and for this reason the claims will be directed as far as possible to the 40 broadest aspect of the invention.

Having described the invention what is claimed as new is:

1. A mechanism for moving an adjustable member to a plurality of predetermined positions, comprising, in combination, two cylinders of unequal length and provided with cooperating pistons and piston rods, a control member operatively connected with the adjustable member and

with both piston rods, whereby the control member will have four adjusted positions, each corresponding to the extreme position of the pistons in the cylinders, and whereby the adjustable member will be moved to positions corresponding to the positions of the control member. 5

2. A mechanism for moving an adjustable member to either of several predetermined positions, comprising, in combination, a differential gear mechanism having two spaced bevel gears 10 mounted for rotation about the same axis, a shaft mounted for rotation about the axis of the bevel gears, a stub shaft attached to the shaft, a bevel pinion rotatably mounted on the stub shaft and in mesh with both bevel gears, means 15 comprising a cylinder and a piston associated with each bevel gear wheel for rotating it through a given arc and in either direction, latching means for holding the other bevel gear against rotary movement while the first is turning, whereby the shaft to which the pinion is attached will be rotated, and means operated by the turning of the last mentioned shaft for moving the adjustable member. 20

3. A mechanism for moving a member for adjusting its position, comprising, in combination, a movable pivot, means for transmitting movement from the pivot to the member to be adjusted, a lever attached to the pivot at a point between its ends, means attached to each end of the lever for moving it, said means comprising a cylinder, a piston located in the cylinder, a piston rod connected with each piston, the other ends of the piston rods being connected with the ends of the lever, whereby the latter will rock on its pivot and move the pivot whenever either or both of the pistons are moved in the cylinders, and means for latching the piston rods at the ends of their movement. 25

4. A mechanism for moving a member for adjusting its position, comprising, in combination, a movable pivot, means for transmitting movement from the pivot to the member to be adjusted, a lever attached to the pivot at a point 30 between its ends, means attached to each end of the lever for moving it, said means comprising a cylinder, a piston located in the cylinder, a piston rod connected with each piston, the other ends of the piston rods being connected with the ends of the lever whereby the latter will rock on its pivot and move the pivot whenever either or both of the pistons are moved in the cylinders, means for latching the piston rods at the ends 35 of their movement, and means for releasing the latching means after the piston has started on its return stroke. 40
